UNITED STATES PATENT OFFICE.

WARREN LEE GOODWIN, OF ATLANTA, GEORGIA.

CHURN.

SPECIFICATION forming part of Letters Patent No. 758,641, dated May 3, 1904.

Application filed May 16, 1903. Serial No. 157,462. (No model.)

To all whom it may concern:

Be it known that I, WARREN LEE GOODWIN, a citizen of the United States, residing at Atlanta, in the county of Fulton and State of Georgia, have invented a new and useful Churn, of which the following is a specification.

This invention relates to means for supporting and operating churning, and has for its object to provide a simple, cheaply-constructed, and easily-applied device whereby a churn-body, preferably of the "stoneware" or crockery form, may be suspended in position to be vibrated to produce the necessary agitation to cause the separation of the butter particles.

The invention consists in certain novel features of construction, as hereinafter shown and described, and specified in the claims.

In the drawings illustrative of the invention, in which corresponding parts are denoted by like designating characters, Figure 1 is a side elevation, and Fig. 2 is a plan view, of the device complete. Fig. 3 is an enlarged sectional detail of the cover and dasher mechanism. Fig. 4 is a section on the line 4-4 of Fig. 3 looking in the direction of the arrow.

The improved device may be employed in connection with any of the ordinary forms of "barrel-churns," but is more particularly applicable for use in connection with the stoneware or crockery churning in common use; but I do not wish to be limited to the use of the device to any specific form or construction of the body of the churn, but reserve the right to its use in connection with any form of churn-body to which it is applicable.

For the purpose of illustration the device is shown applied to an ordinary stoneware or crockery churn-body, (represented at 10.)

The improved device consists of a suspending-harness composed of straps 11 12, of any suitable material, encircling the churn intermediate of its ends and provided with buckles 13 14 of ordinary form to enable the straps to be tightly drawn around the churn. The straps 11 12 are provided with rings 15 16, by which suspension-straps 17 18 are connected, as by "snaps" 19 20 of the usual construction. The straps 11 12 are spaced apart, as shown, and located, preferably, at the center

of gravity, so that the churn will hang without tendency to tilt when suspended. To sustain the straps 11 12, a longitudinal stay-strap 21 will be employed, connected to the straps at opposite sides of the churn and disposed longitudinally thereof, as shown.

Surrounding the churn-body at its open end is a band 22, preferably of metal and with its ends turned at right angles to the band and connected by a clamp-bolt 23, whereby the band 22 may be tightly clamped to the churn. Stoneware or crockeryware churning are generally formed with a bead 24 around the "mouth" or open end, and the band 22 will be placed just in the rear of this bead, the bead thus preventing outward movement of the band and the "swell" of the churn-body preventing any inward movement thereof.

Attached to the band 22 at opposite sides are ears 25 26, extending both in advance and in the rear of the band, the rearward extensions providing means for the attachment of the ends of the stay-straps 21, as shown at 27 28, while the outward extensions are perforated in advance of the open end of the churn, as indicated.

The churn-body is provided with a cover member 29, having a flange 30 extending over the beaded end 24 and with a rubber or other similar flexible packing means 31 between them, as shown. The ears 25 and 26 extend sufficiently in advance of the churn-body to bring the perforations in their outer ends beyond the outer face of the cover member, so that the ends of a lock-bar 32 may be inserted through the perforations and extend over the cover member, as shown. By this means the cover member will be held in position, and to compress it with sufficient force to prevent leakage a clamp-screw 33 is provided, operating through the bar and against the cover member, as shown.

The dasher is represented at 34 and may be of any desired form, but for the purpose of illustration is represented as a simple disk 95 having a shank or stock 35 secured to the inner face of the cover member. The cover member is formed with a central cavity 36, in which the end of the shank is supported and held detachably in position by a catch 37 en-

tering a recess 38 in the dasher-stock, as shown. The catch is pivoted at one end at 39 to the cover member and held yieldably in position in engagement with the recess in the dasher-stock by a spring 40, as shown. The latch-bar is further held in place by a keeper 41, connected to the cover member and under which the latch-bar operates. By this simple means the dasher may be attached and detached when required and when in position is immovable relative to the cover member and churn-body.

The supporting-frame consists of a "head" member 42, having diverging legs 43, 44, 45, and 46 to increase the base-support and prevent any tendency to overturn and provided with longitudinally-extending arms 47 48. The suspension-straps 17 18 are connected to the extremities of the arms 47 48, by which means the churn-body and its attachments are supported between the leg members of the frame, as shown. By this simple means the churn is supported in position to be rapidly vibrated to produce the requisite agitation of the cream to cause the separation of the butter particles, and the ordinary stoneware churn may be utilized as a vibrating churn without danger of breakage and be disposed in position to be very quickly denuded of its suspension-harness when required for cleansing or when not in use.

The strap parts of the device may be leather, canvas webbing, sheet metal, or any other suitable material.

35 The device may be applied to any size or form of churn-body or to churning of any capacity.

Any number of the body-straps 11 12 and

stay-straps 21 may be employed; but generally two of the former and one of the latter will 40 be sufficient.

It will be noted that the bar 32 will be detached with the cover 29 30, while the straps 11, 12, and 21 and band 22 and its clips 25 26 remain on the churn.

Having thus described my invention, what I claim is—

1. In a churn-operating apparatus, a supporting-frame having longitudinal extensions at its upper end, a churn-suspending harness 50 consisting of spaced straps adapted for detachable connection around the body of a churn intermediately of its ends, a stay-strap adapted to be disposed longitudinally of the churn and connected with said body-straps, and suspension-straps connected detachably between said body-straps and the longitudinal extensions of said frame, substantially as described.

2. A churn-suspending means consisting of one or more straps adapted to detachably encircle a churn intermediately of its ends, a band adapted to be detachably arranged around one end of the churn, a stay-strap connected by its ends with the opposite sides of said band and encircling the churn longitudinally and connected with said body-straps, and suspension-straps detachably connected with said body-straps, substantially as described.

In testimony that I claim the foregoing as my own I have hereto affixed my signature in 70 the presence of two witnesses.

WARREN LEE GOODWIN.
